UNITED STATES PATENT OFFICE.

EMERSON W. SINGLETARY, OF MORGANZA, LOUISIANA.

PENCIL-VENDING MACHINE.

1,300,888.

Specification of Letters Patent. Patented Apr. 15, 1919.

Application filed January 2, 1918. Serial No. 209,983.

To all whom it may concern:

Be it known that I, EMERSON W. SINGLETARY, a citizen of the United States, residing at Morganza, in the parish of Pointe 5 Coupee and State of Louisiana, have invented certain new and useful Improvements in Pencil-Vending Machines; and I do hereby declare the following to be a full, clear, and exact description of the invention, such as 10 will enable others skilled in the art to which it appertains to make and use the same.

The present invention relates to pencil vending machines, and aims to provide an improved machine for vending pencils or 15 like articles in which an improved coin controlled mechanism is arranged to regulate the delivery of the pencils upon the deposit of a proper coin in a coin chute of the apparatus.

20 The invention will be more particularly hereinafter described in conjunction with the accompanying drawings, wherein similar reference symbols designate like parts throughout the several views, and in which:

25 Figure 1 is a top plan view of the improved vending machine with the cover removed.

Fig. 2 is a vertical sectional view taken on the line 2—2 in Fig. 1.

30 Fig. 3 is a similar view taken at substantially right angles through the machine on the line 3—3 in Fig. 1.

Fig. 4 is an end elevational view, with 35 parts shown in section and with the locking mechanism housing removed, and showing the parts in one position.

Fig. 5 is a similar view showing the parts in the next following sequence; and

40 Fig. 6 is a perspective view of a key employed in filling the machine.

Referring more particularly to the drawings, 1 and 2 designate ends and 3 and 4 sides, which are assembled on a base 5, and together with a top 6 form a receptacle 7 in 45 which a supply of pencils or other articles to be vended may be kept, and a coin depository 8 separated from the receptacle 7 by a partition 9. The cover 6 is preferably hinged, as indicated at 10, to the receptacle 50 or base, and may be provided with a lock to secure same closed by the proprietor.

On the cover 6 are erected sides 11 and 12, which have locking rods 15 and 16 passing vertically therethrough, and provided 55 at their lower ends with cranks 13 and 14 by which they may be operated, and which are

contained in the base of the machine, as shown in Fig. 3, where they will be secure against unauthorized tampering. The upper extremities of said rods 15 and 16 are bent over at right angles as indicated at 60 17 and 18, and are adapted to engage in openings 17' and 18' made in the members 21 and 22, which, together with the curved metallic piece 23, form the top of the machine. These extremities 17 and 18 are shown in Fig. 3 to lock the top of the machine in place. In Fig. 2 the sides 11 and 12 are shown as provided with recesses 19 and 20 in which the bent extremities 17 and 70 18 are received when the top 23 is to be removed and to which position they are turned by the cranks 13 and 14.

Endless conveyer belts 24 and 25 are fitted to run over pairs of lower drums 26 on a 75 shaft 27 and pairs of upper drums 28 on a shaft 29; which shafts are journaled in the ends 11 and 12. The lower shaft 27 constitutes the drive shaft, and the drums 26 thereon are provided with teeth 30 which 80 receive perforations 31 in the conveyer belts 24 and 25. The various drums 26 and 28 are also preferably made with annular grooves 32 for receiving the inner ends of series of spaced pins 33 fitted through perforations in the conveyer belts 24 and 25. The spaces between these pins provide for receiving the pencils which are delivered therefrom in the manner hereinafter described. 85

A jack 34 fits beneath the upper shaft 29 and is adapted to be moved upwardly in order to tighten the conveyer belts 24 and 25 by a screw 35 threaded in a bearing 36 carried by a cross bar 37 having down 95 turned ends 38 and 39 secured as by the bolts 40 and 41 to the sides 11 and 12.

Blocks 42 and 43 are placed on the cover 6 alongside of the sides 11 and 12; said blocks being formed with semi-cylindrical 100 depressions 44 and 45 in their upper faces in order to provide with front and rear pairs of guide posts 46 and 47, which are erected on said blocks 42 and 43, vertically disposed guideways in which the pins 33 on 105 the belts 24 and 25 will travel, as shown in Fig. 2, while the pencils or other articles held by such pins will be prevented from escaping, except at the slot or gap 48 made in the upper left hand corner of the guideway as shown in Fig. 2, just above the inclined upper ends 49 of the front posts 46. 110

The pins 33 on the left hand side of the conveyer belt, as shown in Fig. 2, are so set therein that they will assume an inclination with their free ends downward, so as to direct the pencils onto the beveled upper ends 49 when same arrive at the gap 48. To aid in ejecting the pencils there are provided displacers in the form of upstanding bars 46', held on the cross bar 37, having forwardly inclined upper ends 47', which extend into the path of the pencils, as indicated in Fig. 2, and which cause the pencils to ride forth into the gap 48.

A delivery chute 50 is comprised between the front ends of the posts 46 and the glass panel 51 fitted in guideways 52 in the side pieces 11 and 12, as shown in Fig. 1. A similar glass panel 53 is likewise slidable in guideways 54 also in said side pieces. These glass panels permit the prospective purchaser to inspect the contents of the machine. At the lower end of the pencil delivery chute 50 is an apron 55 having turned up claws 56 in which to catch the pencil and hold it at a place where it may readily be removed by the purchaser.

The two forward posts 46 are held spaced apart by hollow sleeves 57, having threaded ends which engage the inner ends of right and left screw threaded bolts 58 and 59 passing through the posts and side pieces 11 and 12. Similar sleeves 60 are employed to join the oppositely threaded ends of the bolts 61 and 62. The sleeves are advantageously perforated, as indicated at 60', to receive a pin or other instrument, whereby said sleeves may be turned to draw together or release the bolts to which they are attached.

In one of the sides 12 is a coin chute 63 which communicates at its lower end with the coin depository 8. As shown in Figs. 4 and 5, the side piece 12 is cut away, as indicated at 64, to receive a lever 65 which projects in the path of the coin 66, and which is pivoted as indicated at 67. A spring 68 normally draws the vertical arm 69 of a latch 70 down so that the latch will be directly in the path of the end 71 of a thrust bar 72, which reciprocates in a bearing 73 and has a button 74 by which the purchaser may push the same inwardly. The vertical arm 69 is slotted, as shown at 75, which guides such arm in its vertical movement about a screw 76. A stop 77 is pivoted at 78 on the side 12, and is normally held by a spring 79 in approximately the position shown in Fig. 4, but is adapted to be moved to the position shown in Fig. 5 by an arm 80 when the thrust bar 72 is pushed inward, as illustrated.

A socket 81 is provided between the arm 80 and end of the thrust bar 72 to receive the opposing end of the latch 70, for which see Fig. 5. The upper edge of the thrust bar 72 is beveled as shown at 82, in order

to lift the latch 70 as the stop 77 is removed.

Teeth 83 on the lower edge of the thrust bar 72 are provided to engage a ratchet wheel 84, which is loosely mounted over the shaft 70. A smaller ratchet 85 fits within a recess 86 in the outer face of the larger ratchet 84, and is made fast to the shaft 27. A pawl 87 is carried by the first named ratchet 84 and is yieldingly projected by a spring 88 to engage the teeth of the second named ratchet 85. The ratchet wheel 84 has an annular groove 89 in its rear face, in which lies a spring 90 attached at one end to the ratchet wheel, and at its other end to the side piece 80 12 for the purpose of returning said ratchet wheel to initial position after each subsequent actuation.

In Fig. 6 is shown a key 91 having a shank 92, which fits in a slot 93 in the end of the shaft 27, whereby the proprietor of the machine may independently of the coin controlled mechanism, revolve said lower shaft in order to drive the conveyer belts for the purpose of refilling the machine. The key 91 is passed through an opening 91' in an inclosing casing 92'; which opening is normally closed by a sliding plate 93' to shut out access to the slot 93. The sliding plate 93' is held elevated by a latch 94' which fits in a horizontally elongated opening in said plate, and is bent from the upper end of a vertically turning rod 95' having a crank 96', whereby the latch may be engaged and disengaged.

The operation of the invention is substantially as follows:

The top 6 of the lower part of the machine is first lifted, it being held closed by a suitable lock; after which the proprietor of the machine has resort to the receptacle 7 for a supply of pencils, or other articles with which to fill the machine. Access is then had to the crank 96' and the same is turned, thus rotating the vertical rod 95' and swinging the latch 94' horizontally out of the elongated opening in the plate 93', which releases the plate and permits same to drop down and uncover the opening 91' in the inclosing casing 92'. The key 91 may be then admitted.

When the top 6 of the lower part of the machine is unlocked and raised it also gives access to the cranks 13 and 14, which are turned to rotate the locking rods 15 and 16 and withdraw the bent ends 17 and 18 from the openings 17' and 18' in the upper top. The latter may then be removed. The key 91 is placed with its shank 92 in the slot 93 of the shaft 27, as shown in Fig. 3, and such shaft is revolved by said key in a clockwise direction, viewing the machine from Figs. 2, 4 and 5. As the key 91 is turned the inner ratchet 85 is rotated, also in a clockwise direction, as it is fixed on the shaft 27. The 130

inclined teeth of the ratchet wheel 85 slide beneath the pawl 87 without imparting any motion to the larger outer ratchet wheel 84. This turning of the key will therefore cause 5 the conveyer belts 24 and 25 to be driven, and as the successive spaces between the pins 33 are presented to the upper end of the machine, the proprietor inserts the pencils until all of such spaces are occupied. The key 10 is now removed and the top 23, slide 93' and lower top 6 replaced, the machine being in condition for operation.

A purchaser desiring to secure one of the pencils will place a nickel or coin of other 15 denomination required in the chute 63. As this coin descends it will strike the end of the lever 65 as shown by the coin 66 in Fig. 4, causing the rocking of such lever 65 on its fulcrum 67, which is accompanied by the 20 lifting of the arm 69 and latch 70. The end of the latch 70, which normally extends directly in the path of the end 71 of the thrust bar 72, is thereby raised as far as the stop 77 allows which is shown in Fig. 4 to be to a 25 position opposite the beveled edge 82; the stop 77 preventing so great a movement of the lever 65 as would permit the coin 66 to immediately descend into the coin depository 8.

30 With the parts in the positions indicated in Fig. 4, the thrust bar 72 is now in condition to be forced inwardly to the position in Fig. 5. As said bar 72 is thrust by the button 74, inwardly, the teeth 83 thereon 35 will engage and rotate the ratchet wheel 84. Pawl 87 will simultaneously rotate the smaller ratchet wheel 85 so that the conveyer belts will be advanced the distance of one of the spaces between the pins 33 in order to 40 bring the next successive pencil opposite the gap 48 where it may be delivered to the chute 50.

At the same time that the thrust bar 72 is being moved inward, the beveled edge 82 45 will ride under the latch 70, lifting the latch and swinging the lever 65 to a position where it will release the coin 66 and allow it to pass to the depository 8. The stop 77 will of course be simultaneously forced out 50 of the way by the arm 80. When the thrust bar 72 is released the spring 90 will return the outer ratchet 84 to the original position which will also restore the thrust bar 72 to its outer position, while the spring 79 will 55 return the stop 77 and the spring 68, the latch 70 and lever 65. The restoring movement of the larger ratchet 84 by the spring 90 takes place in a counter-clockwise direction, and the yieldable pawl 87 therefore 60 rides over the inclined faces of the inner ratchet teeth 85 without rotating the same. The parts will then be in condition for subsequent actuation.

It is obvious that those skilled in the art 65 may vary the details of construction and

arrangements of parts without departing from the spirit of my invention, and therefore I do not wish to be limited to such features except as may be required by the claims.

I claim:

1. In a vending machine, the combination of article delivery means, and coin controlled mechanism for said article delivery means including a device attached to said article delivery means, a thrust bar for engaging and driving said device, a latch normally preventing operation of said thrust bar, a coin chute, means in said coin chute connected to said latch for shifting the latter out of locking position, a movable stop adapted to be engaged by said latch when moved to the unlocking position whereby to limit the movement of said last named means and prevent the immediate release of the coin, yieldable means for normally holding said stop in the operative position, means carried by said thrust bar for engaging and shifting said stop to an inoperative position out of the path of said latch, and means also carried by said thrust bar for engaging 90 and causing a further shifting of said latch and connected means whereby to release the coin, substantially as described.

2. In a vending machine, the combination of article delivery means and coin controlled mechanism for said article delivery means including an operating device connected to said article delivery means, a thrust bar, parts carried by said device and thrust bar for interengaging whereby the device may 95 be operated upon the movement of the thrust bar, a latch arranged in the path of said thrust bar to normally prevent the latter's operation, a coin chute, means in said coin chute associated with said latch whereby the 100 latch may be withdrawn from the path of said thrust bar, said last-named means adapted to be actuated by a coin in the chute, a stop for limiting the movement of said latch and last-named means to prevent the immediate release of the coin by the latter, an arm carried by said thrust bar and adapted to engage and remove said stop from said latch, a part on said thrust bar adapted to engage said latch and further 110 shift the same whereupon said latch is adapted to shift the means associated therewith whereby to permit the release of the coin from the latter, means whereby the latch may return to initial position when the 115 thrust bar is restored, and means whereby the stop may also return to initial position on the return of said latch and arm, substantially as described.

3. In a vending machine, the combination 125 of article delivery means, and coin-controlled mechanism for said article delivery means including a device for operating said article delivery means, a reciprocating thrust bar arranged to operate said device, a latch nor-

mally lying in the path and preventing the operation of said thrust bar, a lever connected to said latch, a coin chute adapted to direct a coin into contact with said lever, the 5 coin adapted to rock the lever and lift the latch out of the path of said thrust bar, yieldable means for normally holding said latch in the path of said thrust bar, a pivoted stop engaged by said latch when lifted, 10 said stop preventing so great a movement of the latch and connected lever as to immediately release the coin, yieldable means for holding said stop in an initial position where it may be engaged by said latch, an arm on 15 said thrust bar adapted to strike and remove said stop out of the path of said latch, a part on said thrust bar adapted to engage said latch whereby to further shift the latter and further shift said lever to release the coin, and means for restoring said thrust bar to initial position, substantially 20 as described.

4. In a vending machine, the combination of article delivery means, and coin-controlled 25 mechanism, said mechanism including a device for operating said means, a thrust bar adapted to actuate said device, a coin chute, a coin depository in communication with said chute, a lever having one end projecting 30 into said chute and arranged to be rocked by a coin when placed in the chute, a latch, said latch having a slotted arm, a pin passing through the slot in said arm on which said latch may rock with the lever, the latch normally 35 lying in the path and preventing the operation of said thrust bar, means for yieldingly holding the latch in the path of said thrust bar, said slotted arm of the latch being connected to said lever, a movable stop 40 arranged to limit the movement of the latch and connected lever whereby to prevent the

immediate escape of the coin from the lever into said depository, means for yieldingly holding said stop in a position whereby it may be engaged by said latch, said thrust 45 bar having means whereby the stop is moved away from the latch, said thrust bar also having a part for further shifting the latch and lever whereby the latter may permit the escape of the coin, and means for returning 50 the thrust bar to original position, substantially as described.

5. In a vending machine, the combination of article delivery means, and coin controlled mechanism for said article delivery 55 means including a small ratchet wheel fixed to said article delivery means, a larger ratchet wheel turning loosely with respect to said article delivery means, a yieldable pawl carried by said larger ratchet wheel 60 and arranged to engage with the teeth of the small ratchet wheel, spring means arranged to return said larger ratchet wheel to initial position after each actuation without affecting the smaller ratchet wheel, a 65 thrust bar having teeth arranged to engage with said larger ratchet wheel and to operate the latter, a latch normally lying in the path of said thrust bar, a coin chute, a lever having an end projecting into said coin 70 chute, said lever being connected to said latch and adapted to remove the latter from the path of said thrust bar when a coin is present in the chute, a stop normally in the path of said latch, means carried by said 75 thrust bar for removing the stop from the path of said latch, and means also carried by the thrust bar for raising the latch and moving said lever to release the coin, substantially as described.

80 In testimony whereof, I affix my signature.
EMERSON W. SINGLETON.
